UNITED STATES PATENT OFFICE

134,807

DESIGN FOR A COMBINED DISPLAY AND SALES CABINET

Burton Henry Kennerson, San Jose, Calif.

Application June 29, 1942, Serial No. 107,370

Term of patent 3½ years

To all whom it may concern:

Be it known that I, Burton Henry Kennerson, a citizen of the United States, residing at San Jose, in the county of Santa Clara and State of California, have invented a new, original, and ornamental Design for a Combined Display and Sales Cabinet, of which the following is a specification, reference being had to the accompanying drawings, forming part thereof.

In the drawings:

line 4—4 of Figure 1 and in the direction of the arrows, showing the exterior contour of the band element above the base of the cabinet.

Figure 7 is a sectional view, taken on line 7—7 of Figure 6 and in the direction of the arrows, in order to better illustrate the contour of the article; and

Figure 8 is a similar sectional view, taken along line 8—8 of Figure 6 and in the direction of the arrows.

I claim:

The ornamental design for a combined display and sales cabinet, as shown and described.

BURTON HENRY KENNERSON.
